FIVE POINTED HANDLE FOR FAUCETS

Stephen A. Young, Monticello, Ind. (Flora, Ind.)

Filed Nov. 14, 1958, Ser. No. 53,375

Term of patent 14 years

(Cl. D91—3)

Fig. 1

Fig. 2

Fig. 3

Fig. 4

FIGURE 1 is a top plan view of a five pointed handle for faucets embodying my new design.

FIGURE 2 is a bottom view of the same.

FIGURE 3 is a side elevation of the same.

FIGURE 4 is a sectional view of the same about on the line 4—4 of FIGURE 1.

I claim:

The ornamental design for a five pointed handle for faucets, substantially as shown.
